B. J. BURNETT, OF MOUNT VERNON, NEW YORK.

Letters Patent No. 86,809, dated February 9, 1869.

IMPROVEMENT IN VENTILATORS.

The Schedule referred to in these Letters Patent and making part of the same.

To all whom it may concern:

Be it known that I, B. J. BURNETT, of Mount Vernon, in the county of Westchester, and State of New York, have invented a certain new and useful Improvement in Ventilators, which I denominate "The Centripetal Ventilator;" and I do hereby declare that the following is a full, clear, and exact description of the same, reference being had to the accompanying drawing, forming part of this specification, and in which—

Figure 1 represents a vertical section of my improved ventilator;

Figure 2, a horizontal section of the same, taken as denoted by the line *x x* in fig. 1; and

Figure 3, a similar view through the line *z z*.

Similar letters of reference indicate corresponding parts.

In this, my improvement, which I denominate a centripetal ventilator, power is so concentrated and directed, as that a current of pure atmospheric air is, as it were, injected down and through a centre air-shaft, which action is made constant by the accumulated pressure of air on the windward side, obtained by deflectors in the head of the ventilator.

The pure, cool air, in thus passing down a centre shaft, and assuming its proper position, tends to displace the vitiated air below, and force it up a shaft outside of the centre one, the force of the draught created by the outside current on the leeward side of the head, aiding such action, and being communicated to the area between such fresh and foul air shafts, by conical deflectors in the head.

To this end, or these ends, the invention includes a combination of short upper-air shafts, of a suitable length, proportioned to the diameter of the ventilator, all terminating in the one inside or centre air-shaft; also, a series of deflectors, of conical character, divided into segments, arranged around the outside diameter of the group of upper air-shafts; likewise, in combination with the inside air-shaft, an outside draught-case and flap-valves in the throat of each upper air-shaft, operated by wires or rods from below.

Referring to the accompanying drawing—

A represents the centre air-shaft, down which pure atmospheric air passes to the apartment or chamber to be ventilated.

This shaft is in communication with any desired number of short separate upper air-shafts, *B*, extending up to the head, *C*, of the ventilator, and terminating in throats, *D*, open to the atmosphere, under said head.

The fronts or outsides of these separate upper air-shafts, for a certain distance from their tops below the throats, are of an open character, and provided or fitted with a series of what may be termed conical segmental deflectors, *E*, the same being arranged, it may be said,

in tiers, around the outside diameter of the group of upper air-shafts.

Flap-valves, *F*, operated by wires or rods, *G*, from below, are fitted in the throat of each upper air-shaft.

H is a draught-case or shaft, arranged to surround the centre air-shaft *A*, and extended and enlarged so as to surround, also, as far as the bottoms of their throats, (where it may be made to lap inward,) the upper air-shafts *B*.

From this description it will be seen that the pure atmospheric air, which enters by the throats *D* that lie on the windward side of the ventilator, is projected down the upper air-shafts *B*, with which said throats are in communication, and down the centre air-shaft *A*, said current or currents being restrained by the deflectors *E* from passing into the upper portion or extension of the draught-case or shaft *H*, while the foul air, escaping up the latter shaft or case, naturally takes the course which conducts to the leeward side of the ventilator, and, in so doing, has to pass through between the deflectors *E*, which lie or are arranged on said side, and out through their upper air-shafts.

This produces a sort of eddy in the leeward upper air-shafts *B*, which, without impeding the escape of the vitiated air, operates to prevent any upward current through the shaft *A*.

The flap-valves *F*, arranged as shown and described, serve to direct and control the current and draught through each or all of the upper air-shafts *B*, on the windward and leeward sides of the ventilator, and, being separately manageable from below, admit of the most perfect control.

What is here claimed, and desired to be secured by Letters Patent, is—

1. The combination, with a centre or common air-shaft, *A*, of a series of upper air-shafts *B*, arranged to open at their lower ends into, or so as to communicate with said shaft, and terminating at their tops in side openings or throats, *D*, substantially as specified.

2. The combination of the centre shaft *A* and outside or surrounding draught-case or shaft *H*, substantially as specified.

3. The conical segmental deflectors *E*, arranged around the group of air-shafts *B*, in combination with the centre shaft *A*, and outside shaft or draught-case *H*, essentially as shown and described.

4. The flap-valves *F*, arranged and operated as described, in combination with the separate upper air-shafts *B* and centre shaft *A*, substantially as herein set forth.

B. J. BURNETT.
